[57] CLAIM

The ornamental design for a microscope laboratory slide, as shown and described.

DESCRIPTION

FIG. 1 is a perspective view of my new, original ornamental design for a microscope laboratory slide, transparency shading being omitted from the specimen well portions for ease of illustration;

FIG. 2 is a top plan view of the slide;

FIG. 3 is a right side elevational view of the slide;

FIG. 4 is a rear elevational view of the slide;

FIG. 5 is a bottom plan view thereof.

*Fig. 1.**Fig. 3.**Fig. 2.**Fig. 4.**Fig. 5.*
